UNITED STATES PATENT OFFICE.

CHARLES ORME BASTIAN, OF LONDON, ENGLAND, ASSIGNOR TO COOPER HEWITT ELECTRIC COMPANY, OF HOBOKEN, NEW JERSEY, A CORPORATION OF NEW JERSEY.

ELECTRIC VAPOR APPARATUS.

1,079,926.

Specification of Letters Patent. Patented Nov. 25, 1913.

Application filed December 19, 1905. Serial No. 292,480.

To all whom it may concern:

Be it known that I, CHARLES ORME BASTIAN, electrical engineer, a subject of the King of Great Britain, residing at 75 5 Brondesbury road, London, England, have invented certain new and useful Electric Vapor Apparatus, of which the following is a specification.

This invention relates to improvements 10 in electric vapor lamps, and it consists in various novel details of construction and combinations of parts more fully hereininafter described and particularly pointed out in the claims, which features also singly or 15 in combinations contribute toward the improvement of electric vapor lamps of the character set forth in Bastian and Salisbury's U. S. patent application, filed 17th, August, 1903, Serial No. 169,792, and U. S. 20 application filed 25th August, 1904, Serial No. 222148, and my subsequent British patents for such lamps, Nos. 24023 of 1903, 5892 cf. 1904, and 9718 of 1904, but the said improvements may be used in conjunction 25 with other forms of electric vapor lamps or electric vapor apparatus to which the same may be applicable either wholly or in part.

For the sake of brevity I refer to the tube 30 containing the mercury and electrodes and in which the arc is formed during working as the "burner" and this irrespective of whether the apparatus be used for giving light or for any other purpose such as rectifying or rupturing electric circuits.

In such electric vapor apparatus I have found that unsteadiness and accidental extinction of the arc may be caused by the 35 passage through the arc of particles of unvaporized or un-ionized mercury or other 40 matter forming the electrodes, all of which matter for the sake of brevity I will hereininafter refer to as "mercury"; and I prevent this by forming the container tube at 45 the upper or negative electrode of such small bore as to retain in it the unvaporized or un-ionized mercury, which I will hereininafter refer to as liquid mercury. I also construct 50 the heat radiating surfaces and the cross-sectional areas of the positive and negative electrodes in such proportion one to the other, as to cause a higher temperature at one electrode than at the other; so that the

evaporation of mercury from the one, and the condensation of mercury at the other, 55 will automatically compensate for and rectify any increase or diminution of mercury, as the case may be, that may be due to that effect of the electric current, which I may conveniently describe as a kind of electrolytic, or ionizing effect mentioned in the 60 said prior patents. This automatic compensation seems to be due to a fall, or rise, of temperature in each electrode, as the volume of mercury at that electrode varies 65 and the said changes in temperature seem to be due to one or both of two causes:—First, as the volume of the mercury decreases, the active electrode surface is brought, under certain conditions, into a 70 more effective relationship or closer proximity with the greater relative heat radiating surfaces. Or second, when the electrode is bulb-shaped, for example, as the volume of mercury decreases, the area, or cross-section, 75 of the said active electrode surface is increased; and hence the heat caused by the passage of the current is diminished and the temperature falls. The reverse action takes 80 place if the volume of the bulb shaped electrode is increased beyond the level of the maximum surface for any one position.

Now, by my present invention, I retain 85 practically constant quantities of mercury, at each electrode, and thus maintain a condition of equilibrium, and consequently secure a perfectly steady working of my apparatus. Since only mercury in a condition of vapor or in an ionized condition is permitted to pass through the arc path after 90 the current has once been started, my lamps will keep constantly in operation with only a small proportion of steadyng resistance sufficient to absorb about 15% of the total 95 energy in the circuit.

I may advantageously form the cups, or receptacles, for containing the mercury at the electrodes, in the form of tubes of varying cross-section at practically right angles to the arc path. And the said arc stream 100 tube may be of any desired size in cross-section and may be adapted to operate either in a horizontal or in a slightly inclined position. That is to say, when the burner is tilted to start the arc it may continue in 105 such tilted position, so that a greater or less

electrode surface may be exposed according to the quantity of solid mercury the receptacles may contain at any time.

When a symmetrical column of mercury is 5 closely confined within (*i. e.* closely surrounded by) an exhausted glass tube of symmetrical bore, it exhibits a very considerable amount of cohesion throughout its length, (even if held vertically or there- 10 about). And when it is desired to separate such column at any given point, it is ad- vantageous to restrict the tube at that point, *i. e.* render the column other than symmet- 15 rical at said point, or otherwise make such point the weakest point in the column of mercury. For instance, I may interpose a device, or piece of glass, or any suitable material; or, draw out the glass tube at the desired point, to reduce the mercury cross- 20 section, and so render that point the weakest in the mercury column; or, I may produce this weakest point by providing a head of mercury at such point.

With all classes of mercury vapor lamps, 25 or other electric vapor apparatus, it frequently happens that a small quantity of air, or other gas, remains within the container, or occluded in the mercury after the lamp has been sealed, and taken off the 30 pump; but according to this part of my present invention, I form, or arrange, in any suitable position on the lamp, an enlargement or trap, into which the air may be transferred by careful manipulation, and 35 retained there by liquid mercury, which latter may form one of the electrodes; and the air thus trapped, is thereby prevented from getting into the arc and disarranging the normal operation of the latter. If the 40 said enlargement, or trap, be attached to the top of the anode (or cathode) it serves the double purpose of a cushion for the mercury, in such electrode forcing the mercury back when the circuit is broken and pre- 45 venting it from sticking in the tube.

When starting two or more of these burners in parallel by the "tilting method," I find it is practically impossible to cause both arcs to strike simultaneously; which, of 50 course, is necessary, and I, therefore, strike one arc, and then separate it, or sub-divide it, into two or more separate paths; and I may arrange this for example, by forming the tubular container Y -shaped with two 55 positive electrodes and one common negative electrode; a chamber being provided at each of the positive ends of the burner for receiving the solid mercury removed from the arc path; and the bore of the tube may be suitably enlarged between the point at 60 which the arcs unite and the negative electrode. I find it advantageous to fix the position of the negative electrode, and cause the mercury to move toward or past the

positive electrode or electrodes, when the 65 lamp is put into operation; and I maintain a constant length of arc between the elec- 70 trodes, and cause the pressure within the arc to vary the position of the solid mercury situated in, or moved into a suitable recep- 75 tacle behind the positive electrode or elec- trodes; and solid mercury may be provided, so as to keep the quantity of solid mercury at the positive electrode constant or approxi- mately so.

The heat radiating surface of mercury vapor lamps or other electric vapor apparatus may be conveniently regulated by forming the glass or other envelop inclos- 80 ing, or surrounding the arc, with a con- stant internal cross-section; but, with a thicker or thinner wall, according to whether it is desirable to provide more or less heat radiating surface.

It has been proposed to start mercury 85 vapor apparatus by means of a shunt electro-magnet, and to leave the latter in circuit during subsequent operation; but, I find it desirable to arrange for the pressure within the arc to automatically cut out of 90 circuit the shunt electro-magnet, during such time as the lamp is in operation, and to restore the connection when the current is switched off and the pressure subsides through cooling; and I may, conveniently, 95 effect this by causing the pressure to act on a body of mercury behind the positive electrode as aforesaid; for example, by separating the electro-magnet circuit connection from the positive electrode.

Referring to the accompanying drawings:—Figure 1 is a diagrammatic elevational view partly in section of a burner showing the arrangement for producing differential heat radiating surfaces at the 100 respective electrodes and a varying cross- sectional area of the active electrode surfaces. Fig. 2 shows another form of burner, arranged as a U-shaped tube with an enlargement or bulb at each end of such U- 110 shaped tube. Fig. 3 shows another form of burner arranged approximately in a circular form with an enlargement or bulb at each end of the circular container tube. Fig. 4 is a side elevational view partly in 115 section of the burner shown in Fig. 3, and Figs. 5 and 6 show different modifications in the type of burner shown in Fig. 1, as is more fully described hereinafter.

Referring now more particularly to Fig. 120 1:—*a*, is the container tube, which is of small bore, adapted to retain the unvaporized, or un-ionized mercury within it by the pressure of the arc stream and surface ten- sion, between said small tube and the mer- 125 cury; or to otherwise prevent said mercury passing through the arc path during the operation of the burner. The electrode *b*

which I have marked as the negative electrode is provided with an enlargement b^1 , while the other electrode c which I have marked as the positive electrode is provided 5 with an enlargement c^1 and also with a bulb d , for containing that part of the mercury which is displaced from the arc path when the burner is in operation.

Assuming that the burner has been tilted 10 until the mercury from the bulb d has filled the small bore tube a , and thereby completed the circuit from b to c , and then the burner has been restored to the position shown in the drawings, or thereabout, the action is 15 such that at the starting up of the burner the mercury in the enlargement c^1 will be at about the level shown in dotted lines at c^2 and the mercury at the negative electrode will be about the level shown by the dotted 20 lines b^2 .

By the action of the electric current throughout the operation of the apparatus mercury will tend to be transferred from the positive electrode to the negative electrode 25 and consequently the mercury will tend to accumulate at the negative electrode up to say the level indicated at b^3 and simultaneously diminish at the positive electrode. As this action proceeds, eventually, the level of 30 the mercury at the positive electrode will descend in the enlargement c^1 to say the level indicated at c^3 , at which point, it will be obvious that a larger electrode surface is presented than when said electrode was at the 35 level c^2 ; and consequently, the active electrode surface is brought the nearer to the general body of liquid mercury in the bulb d . Therefore, an increased cooling effect on the electrode surface C^3 is obtained, in addition 40 to increasing the active electrode surface; and the heat due to the passage of the current through the mercury at this active surface is at the same time diminished. It consequently results that the temperature of this 45 electrode falls and prevents losses by vaporization. As the reverse action simultaneously takes place at the other electrode, a state of equilibrium is established between the amount of mercury lost and gained by each 50 electrode from whatever cause. It does not follow that this point of equilibrium will be reached exactly at the levels of the mercury indicated in Fig. 1, but if the burner be arranged so that the relative cooling effect 55 be increased at one electrode, as the mercury is transferred from that electrode; then, it can be made to automatically arrive at the aforesaid point of equilibrium and thereafter continue, so to operate. For ex- 60 ample, with a burner wherein the container tube a is of, say, three-sixteenths of an inch bore, then the enlargement c^1 at the positive electrode c , may increase from three-six- teenths of an inch up to five-sixteenths of an

inch or more. By providing a similar enlargement b^1 at the negative electrode b , the burner is enabled to work with the current reversed.

In Fig. 2, the small bore container tube a is shown with enlargements or bulbs e and f practically of equal form and dimensions at each end of such U-shaped tube. The quantity of mercury is advantageously such as to completely fill or rather more than fill 70 each enlargement e and f when the lamp is tilted, and in operation the mercury is gradually transferred from the positive electrode e , so that the level of the surface of the mercury at the positive electrode gradually recedes toward or into the enlargement e , at 75 the positive electrode, while the level of the mercury at the negative electrode f , is gradually removed farther from said negative electrode, as indicated in the drawings, until the point is reached that the mercury at the 80 level f^1 becomes so much hotter than the mercury at the level e^1 that the equilibrium as mentioned above is established.

In Figs. 3 and 4 the small bore container tube a is shown arranged in a circular form 90 or thereabout with a positive electrode e and negative electrode f , each of the same size or approximately so with enlargements or bulbs e^* f^* located outside the path of the arc stream. In this arrangement the mercury lies around the tube a before the lamp is started, and normally connects the electrodes e and f , while a small bore tube may be used with sufficient mercury to normally 95 fill said tube in order to connect the two electrodes e and f . When the burner is started by tilting the same the mercury is separated at or about centrally between the two electrodes and is caused to run back into each of the respective bulbs e^* f^* , and 100 the arc stream extends from the region of the electrode e around the circular tube to or near the electrode f . As the mercury diminishes at the positive electrode e , and accumulates at or near the electrode f , the 105 arrangement is such that a similar action takes place as before described, and a point of equilibrium is reached at which the respective levels of the electrode surfaces remain constant or practically so throughout 110 the operation of the burner. On the container tube a , at about midway between the electrodes e and f , I arrange a small vertical tube g terminating in a bulb g^1 which is 115 in closed connection with the interior of the said tube so that when the mercury is caused or allowed to pass around the container tube a to connect the electrodes e and f , part of 120 said mercury will be forced up the tube g and form a small head of mercury. When the burner is tilted the capillarity of the tubes will cause the mercury to positively 125 divide at the point immediately below this

said small column of mercury, and thus insure starting the arc stream in the tube about centrally with respect to the electrodes, and also insure the positive starting 5 up of the burner in a regular manner. In the manufacture of these burners I find it advantageous to utilize this vertical column g and enlargement g^1 for the purpose of connecting to the vacuum pumps and the 10 subsequent sealing off.

In the arrangement shown in Fig. 5, which is similar to Fig. 1 with certain modifications, the container tube a is shown straight with an enlargement b^1 at the negative electrode 15 b and with a pocket c^4 near the positive electrode c . In place of the enlargement c^1 , shown in Fig. 1, the bulb d for receiving the mercury is shown in a slightly different position to that of the bulb d in 20 Fig. 1. The operation of this burner is similar to that already fully described with reference to Fig. 1, the mercury in the pocket c^4 producing a cooling effect at or near the positive electrode c .

25 Referring now to Fig. 6:—Instead of providing enlargements such as b^1 and c^1 , at or near the electrodes as before described, I may obtain similar or equivalent effects by providing an enlarged surface or mass such 30 as the swellings or thickened glass walls b^x c^x , as illustrated in Fig. 9; or these swellings may be formed of other suitable material, or suitable portions of the surfaces may for the purpose hereinbefore described 35 be prepared in any of the well known ways, either to retard or to encourage radiation of heat. In this case advantage is not necessarily taken of increasing or diminishing the active electrode surface so as to 40 moderate the temperature.

It will be obvious that if desired, and where suitable, the current may be passed in reverse direction through any of the burners illustrated especially in burners constructed 45 in the manner described and illustrated in Figs. 1 to 4. Therefore, mercury displaced from one electrode, owing to the difference in electric potential between the electrodes, can be replaced with mercury displaced in 50 the opposite direction owing to the difference in heat potential between the electrodes, and by constructing the burner so as to utilize this discovery I am thereby enabled to establish and maintain constant quantities of 55 electrode material at each electrode respectively, without the passage of solid mercury through the arc path.

It is evident that changes in the details 60 of construction and arrangement of parts may be made by those skilled in the art without departing from the spirit of my invention, and therefore I do not wish to be limited to such features except as may be required by the claims.

What I claim is:—

1. In a vapor lamp the combination with an anode, of a cathode chamber containing an active fluid, said electrodes being so relatively proportioned that the heat dissipating capacity of the cathode chamber bears the same relation to the corresponding heat dissipating capacity of the anode that the heat generated by one of said electrodes bears to that generated at the other.

2. In a vapor lamp, the combination with 75 an anode chamber containing an active fluid, of a cathode chamber containing an active fluid, said electrodes being so relatively proportioned that the heat dissipating capacity of the cathode chamber bears the same relation to the corresponding heat dissipating surface of the anode chamber that the heat generated at the cathode bears to that generated at the anode.

3. In a vapor lamp, the combination with 85 an anode, of a cathode, said electrodes being so relatively proportioned that the heat dissipating capacity of the cathode bears the same relation to the corresponding heat dissipating capacity of the anode that the heat generated at one of said electrodes bears to that generated at the other, and means for regulating the dissipation of heat from one of said electrodes.

4. In a vapor lamp, the combination with 95 an anode, of a cathode, said electrodes being so relatively proportioned that the heat dissipating capacity of the cathode bears the same relation to the corresponding heat dissipating capacity of the anode that the 100 heat generated at one of said electrode bears to that generated at the other, and means for automatically regulating the dissipation of heat from one of said electrodes.

5. In a vapor lamp, the combination with 105 an anode, of a cathode, said electrodes being so relatively proportioned that the heat dissipating capacity of the cathode bears the same relation to the corresponding heat dissipating capacity of the anode that the 110 heat generated at the cathode bears to that generated at the anode, and means for automatically regulating the dissipation of heat from the cathode.

6. In a vapor lamp, the combination with 115 an anode, of a cathode, said electrodes being so relatively proportioned that the heat dissipating capacity of the cathode bears the same relation to the corresponding heat dissipating capacity of the anode that the heat 120 generated at the cathode bears to that generated at the anode, and means controlled by the cathodic aigret action for automatically regulating the dissipation of heat from the cathode.

7. In a vapor lamp, the combination with 125 an anode, of a cathode chamber containing an active fluid, and means controlled by the

cathodic aigret action for automatically regulating the dissipation of heat from the cathode.

8. In a vapor lamp, the combination with an anode, of a cathode chamber, said electrodes being so relatively proportioned that the heat dissipating capacity of the cathode bears the same relation to the corresponding heat dissipating capacity of the anode that the heat generated at the cathode bears to that generated at the anode, and means whereby the heat dissipating capacity of the cathode chamber is automatically regulated for changes in outside temperature.

15 9. In a vapor lamp, the combination with an anode, of a cathode chamber, said electrodes being so relatively proportioned that the heat dissipating capacity of the cathode bears the same relation to the corresponding heat dissipating capacity of the anode that the heat generated at the cathode bears to that generated at the anode, and means controlled by the cathodic aigret action for automatically regulating the heat dissipating capacity of the cathode for changes in outside temperature.

10. In a vapor lamp, the combination with an illuminating tube, of an anode, a cathode chamber, a narrow intermediate tube connecting the illuminating tube and the cathode chamber, an active fluid in the cathode chamber and partially filling the intermediate tube, whereby the agitation of the fluid in the cathode chamber is varied automatically when the fluid is added to by condensation or subtracted from by distillation.

11. In a vapor lamp, the combination with the horizontal illuminating tube, of an anode, a cathode chamber, a narrow upwardly inclined intermediate tube connecting the illuminating tube and the cathode chamber, an active fluid in the cathode chamber and partly filling the intermediate tube.

12. In a vapor lamp, the combination with an illuminating tube, of an anode chamber at one end of said illuminating tube, a cathode chamber, a narrow intermediate tube between the other end of said illuminating tube and said cathode chamber, and

a metal liquid in said anode chamber, said cathode chamber and said narrow intermediate tube, the heat dissipating surfaces of said anode chamber and said cathode chamber being in proportion to the heats developed therein, said narrow intermediate tube being adapted to regulate the agitation of the metal in said cathode chamber by the cathodic aigret action, and thereby to regulate the heat dissipating capacity thereof.

13. In a vapor lamp, the combination with an anode, of a cathode chamber containing a liquid electrode, and means for automatically regulating the heat dissipating capacity of said cathode.

14. In a vapor lamp, an anode chamber containing a liquid, a cathode chamber containing a liquid, the chambers being so proportioned that during working an equilibrium is automatically maintained between the quantities of liquid at the electrodes without the passage of the liquid in liquid state between the chambers, and means for automatically maintaining this equilibrium when the outside temperature varies.

15. In a vapor lamp, an illuminating tube stationary when the lamp is in operation, an anode chamber containing mercury, a cathode chamber containing mercury, the heat dissipating surfaces of the chambers being so proportioned that during working an equilibrium is automatically maintained between the quantities of the mercury at the electrodes.

16. In a vapor lamp, an illuminating tube stationary when the lamp is in operation, an anode chamber containing mercury, a cathode chamber containing mercury, the heat dissipating surfaces of the chambers being so proportioned that during working an equilibrium is automatically maintained between the quantities of the mercury at the electrodes, and means for automatically maintaining said equilibrium when the outside temperature varies.

In witness whereof I have hereunto set my hand in presence of two witnesses.

CHARLES ORME BASTIAN.
